Primary Examiner—James R. Largen*Attorney, Agent, or Firm*—Patula & Associates[57] **CLAIM**

The ornamental design for a bathtub, as shown and described.

DESCRIPTION

FIG. 1 is an exploded perspective view taken from the top and front of a bathtub showing our new design;
 FIG. 2 is a perspective view taken from the top and front thereof, showing the seat in position;
 FIG. 3 is a front elevational view thereof;
 FIG. 4 is a rear elevational view thereof;
 FIG. 5 is a right side elevational view thereof;
 FIG. 6 is a left side elevational view thereof;
 FIG. 7 is a bottom plan view thereof;
 FIG. 8 is a top plan view of FIG. 2; and,
 FIG. 9 is another top plan view thereof with the seat removed for convenience of illustration.

FIG. 1

FIG. 2

FIG.3

FIG.4

FIG.5

FIG.6

FIG. 7

FIG. 8

FIG.9
